UNITED STATES PATENT OFFICE

CHARLES M. MAPES, OF RUTHERFORD, NEW JERSEY, AND EDMUND BRITTAN, OF NEW YORK, N. Y.; SAID BRITTAN ASSIGNOR TO SAID MAPES

SWIMMING POOL

Application filed February 23, 1927. Serial No. 170,398.

The invention is directed to features of construction whereby a suitable reservoir may be employed either as a skating rink or as a swimming pool. Among the features of the invention is the provision of means whereby the conversion from the use of the reservoir for one purpose to use for the other purpose may be readily effected.

In carrying the invention into effect in a form which we now regard as a preferred form thereof, we provide a temperature controlling means in cooperative relation with the floor of the reservoir for the purpose primarily of freezing a layer of ice on the said floor to adapt the reservoir as a skating rink. For the purpose of converting the reservoir for use as a swimming pool, we provide a floor arranged for ready placement in the reservoir and ready removal therefrom, this superposed floor being suitably supported at an angle to the main floor so as to provide a varying depth for the swimming pool. The said superposed floor is preferably perforated so as to provide for a circulation of the water in the pool. Certain of the side walls of the reservoir are preferably of step formation so as to provide for the entrance and exit of persons to the reservoir, whether the same is used as a swimming pool or as a skating rink and also to provide for the seating of spectators for the skating rink. The said superimposed floor is preferably designed to interfit with the said step formation so as to provide an uninterrupted surface for the floor of the swimming pool.

For a better understanding of the invention, reference is had to the accompanying drawing, in which Fig. 1 is a sectional view of the reservoir when being used as a swimming pool; Fig. 2 is a similar view showing the reservoir adapted for use as a skating rink; Fig. 3 is a top plan view of the reservoir when used as a swimming pool, showing the removable perforated floor and the manner in which this floor interfits with the steps forming two opposite side walls of the reservoir; Fig. 4 is a side sectional view taken longitudinally of Fig. 3; and Fig. 5 is a similar sectional view showing the reservoir adapted for use as a skating rink.

Referring to Figs. 1 and 2, the reservoir 10 is preferably, although not necessarily, of rectangular shape and of such dimensions that the area of the floor 11 is at least as large as that required for playing the game of ice hockey. The pipes, such as indicated by 12, are preferably embedded in the floor 11 and provide a means for the circulation of a refrigerating medium for freezing a layer of ice on the floor 11 to adapt the reservoir 55 for use as a skating rink as shown in Fig. 2. The reservoir 10 is preferably of concrete as that provides a suitable water tight structure and one which can be readily repaired as cracks develop or a flaking off occurs. We 60 would have it understood that although we have shown the temperature controlling piping as embedded in the concrete floor, and regard this as a preferable construction, the invention is not necessarily thus limited, since 65 the piping may be laid upon the floor. We 70 also contemplate that this temperature controlling circulating system may be used for governing the temperature of the water when the reservoir is being used as a swimming 75 pool.

In order to convert the reservoir from the use as a skating rink, as shown in Fig. 2, to the use as a swimming pool, as shown in Fig. 1, the circulation of the refrigerating medium 80 through the piping 12 is stopped and the superposed floor 13 is placed in position in the reservoir. This floor 13 is of any suitable material and if the floor is of wood it is desirable to impregnate the same with some fluid 85 repellent medium such as sulphur. Sulphur used as air impregnating medium has the further advantage of adding considerable weight so that the floor will remain in position by its own weight when the reservoir is filled with 90 water. The floor 13 is held in a position at an angle to the floor 11 so that the effective depth of the swimming pool varies from a minimum at one end thereof to the full depth 95 of the reservoir at the other end thereof. In this way, beginners may safely use the shallow end of the pool and the more experienced swimmers use the deep end of the pool. Although no indication thereof has been made on the drawing, it will be obvious that a 100

diving platform or diving platforms may be located at the deep end of the pool, the height of such platforms to bear a safe relation to the depth of the pool.

5 The floor 13 is supported and held in its indicated position by suitable means. We have indicated in Fig. 1 our preferred means as the sectional supporting structure 14. This structure is formed of a suitable number of uprights of gradually varying heights and cross members secured thereto for the purpose of holding the uprights in position with respect to the floor and with respect to each other. It will be found desirable to make 10 the floor 13 of a number of sections suitably marked for identification and also mark the uprights and cross members in a suitable manner for identification so that the floor sections and the support sections may be assembled and secured together in accordance with 15 a definite plan. Thus, the ready removal or installation of the floor and its supporting structure is facilitated. The supporting structure, if of wood, is also suitably impregnated with a water proofing material, such 20 as sulphur.

The construction shown in Figs. 3 and 4 embodies the general features heretofore referred to in connection with the construction 30 shown in Figs. 1 and 2 and similar parts and parts having similar functions are designated by the same numerals as corresponding parts of Figs. 1 and 2. Figs. 3 and 4 show the side walls 15 and 16 of the reservoir 10 as of a 35 step formation and the superposed floor 13 as of such a shape as to interfit with the steps of the side walls. These steps serve a double purpose since they provide a means of entrance and exit to the reservoir whether the 40 same be used as a swimming pool or as a skating rink, and also serve as seats for spectators. Of course they provide a greater seating capacity when the reservoir is used as a skating rink than when it is used as a swimming 45 pool, because the water depth is less in one case than in the other, but the capacity may easily be increased by increasing the depth of the reservoir or by making the side walls of greater height and running the steps to the 50 top edge thereof. Obviously, the steps may so extend from the floor 11 to the top of the side walls even though this may mean either a reduction of the bottom area or the provision of a wider reservoir. When the steps are 55 not run to the top edge of the reservoir, as in the present instance, ladders may be used to connect the top steps with the top of the reservoir.

The superposed floor 13 is preferably provided with perforations 17, as indicated, for the purpose of permitting a comparatively free circulation of the water in the reservoir when used as a swimming pool. The depth of the water in the pool may be nearly equal 65 to the height of the walls of the reservoir.

In Fig. 5, the superposed floor and its supporting structure of Fig. 4 have been removed so as to adapt the reservoir for use as a skating rink. The steps 16 are indicated as an integral part of the side wall. While this is regarded as a preferable construction, we would have it understood that this integral construction is not essential since the steps may be of the removable type. However, since there is no necessity of removing these steps they are preferably formed as an integral part of the side wall. 70 75

While the drawing does not show the same, we would have it understood that we contemplate that suitable inlet and outlet passages are to be provided for the water of the swimming pool. Such provisions are customary and have therefore not been shown. A satisfactory method of forming the ice for the skating rink is to cause the refrigerating medium to circulate through the piping 12 until the floor 11 is at a temperature below 32° F. and then spray the water on the floor. A layer of several inches of ice can be formed comparatively quickly and this thickness is suitable for skating. 80 85 90

What we claim as new and desire to secure by Letters Patent of the United States is:

A swimming pool construction comprising a substantially rectangular and relatively 95 deep water-tight tank having steps on two opposite sides leading to the bottom thereof and extending the full length of said sides to provide seats for spectators as well as means for entrance and exit, and a removable inclined sectional and perforated platform supported within the tank interfittingly with the steps on opposite sides. 100

In witness whereof, we have hereunto set our hands this 14th day of February, 1927. 105

CHARLES M. MAPES.
EDMUND BRITTAN.
